BUILDING CONSTRUCTION

William B. North, East Orange, N. J.

Application October 10, 1942, Serial No. 461,524

6 Claims. (Cl. 108—9)

This invention relates to building constructions and more particularly pertains to roofing and siding constructions for buildings, enclosures and the like, and to methods of applying such constructions.

The invention provides a roof and siding construction of the shingle type, employing composition, slate, wood, asbestos and cement shingles, or shingles of other materials, wherein the shingles are disposed and secured in such manner that only a single overlapping of the successive rows of shingles is required, and no mechanical securing devices such as clips or the like, are required for the butt ends of the shingles, thereby providing a construction which is economical of material but in which there is no sacrifice of durability. Roof and siding constructions embodying the invention are of considerable less weight than equivalent conventional arrangements and they can be applied with less manual effort and with relatively inexperienced labor. The composite construction embodying the invention not only provides an exterior exposed surface, but also provides insulation against transmission of heat therethrough, and may constitute the entire structure of the wall or roof other than the structural supporting members such as studs, rafters, and the like.

The invention will be understood from the following description when considered in connection with the accompanying drawing forming a part thereof, and in which:

Fig. 1 is a partial plan view of a roof or siding construction embodying the invention;

Fig. 2 is a sectional view taken on line 2—2 of Fig. 1;

Fig. 3 is a view similar to Fig. 1 showing another form of the invention;

Fig. 4 is a sectional view taken on line 4—4 of Fig. 3;

Fig. 5 is a view similar to Fig. 1 but showing a further form of the invention;

Fig. 6 is a sectional view taken on line 6—6 of Fig. 1, and

Fig. 7 is a plan view of another form of the felt utilized with the form of the invention shown in Figs. 5 and 6.

Like characters of reference refer to the same or to similar parts throughout the several views.

Referring first to Figs. 1 and 2 of the drawing, reference character 10 designates a base of closed sheathing upon which the roof or siding construction of the invention is laid. It will be understood that other structures may be employed as the base for the roof or siding con-

struction, such as open sheathing or other arrangements. In laying the first course, a strip of water-proof material, such as asphalt, saturated and/or coated felt 11, having a width approximately equal to the length of the shingle to be used, is applied to the base 10 and preferably is tacked down to hold it in place. A course of shingles 12 are laid in side-by-side relationship over the felt strip 11, and are secured at their head ends to the base by driven elements, such as nails 13. Water-proof cement 14 of any suitable composition or mixture, is applied by a pressure gun or otherwise, to the head end portions of the shingles 12, and a second strip of felt 11 is laid over the cemented portions of the first course of shingles, as shown, and its lower edge is adhesively secured to the head ends of these shingles. A second course of shingles 12 is then laid over the second strip of felt, and the shingles are secured at their head ends by driven elements 13. Cement is applied to the head end portions of the shingles, and another strip of felt is laid and adhered to the second course of shingles, and so on in this manner until the roof or siding is completed.

The form of the invention shown in Figs. 3 and 4 is like the form shown in Figs. 1 and 2, excepting that water-proofing cement 15 is also applied to the lower edge of each felt strip 11 to adhesively secure the butt ends of the shingles 12 to the felts. The roof or siding construction will be applied in the same manner as previously described, excepting that the cement 15 is applied to the felt after the felt strip is laid and before the overlying shingle course is laid.

In the form of the invention illustrated in Figs. 5 and 6, felt 16, instead of being imperforate or substantially so, as in the forms previously described, is provided with a plurality of relatively closely spaced, small apertures 17 in its lower edge portion, to receive and to retain a suitable water-proof cement which will adhere the felt 16 to the base 10, or to the head ends of the shingles in the overlapped course, and will adhere the butt ends 45 of the shingles 12 to the felt and to the base 10 or the shingles in the overlapped course. As shown in Figs. 5 and 6, the lower edge of the felt is provided with two rows of apertures 17 with the apertures in one row being staggered with respect to the apertures in the other row. More than two rows of apertures may be employed, if desired, and the apertures may be arranged otherwise than in longitudinally extending rows, as shown. With two rows of apertures as shown in Fig. 5, the apertures may have a diameter of

one-quarter inch, more or less, for satisfactory results, although apertures of other diameters may be used.

In applying the roof or siding construction of the form shown in Figs. 5 and 6, a strip of felt 16 is laid on the base 10, and the water-proof cement is applied by a pressure gun or otherwise, to the apertures 17 and to the felt immediately adjacent the apertures. The first course of shingles 12 is laid on the felt 16 and each shingle is secured at its head end to the base by nails 13 or other driven elements, after which another strip of felt 16 is laid with its lower edge portion overlapping the head ends of the first course of shingles, cement is applied to the apertures 17 and the adjacent felt areas, another course of shingles 12 is laid over the second strip of felt 16, the shingles are secured to the base by nails 13, and so on in this manner until the roof or siding construction is completed. The felt may be indented very slightly in the area to which the cement is applied to guide in the application of the cement to the felt. The felt will absorb the oils in the cement and prevent the cement from running down the shingles.

As shown in Fig. 7, the felt 16 may have but a single row of apertures 18. For satisfactory results, these apertures may be of the order of three-eighths inch in diameter, although the invention is not limited to apertures of this diameter.

From the foregoing, it will be perceived that a sound and durable roof or siding construction is provided, which is economical of materials and requires no mechanical securing means, such as 35 clips or the like, for the butts of the shingles.

Although the invention is disclosed as embodied in a roof or siding construction in which each course overlaps but one other course, it will be understood the invention is not restricted thereto, but may be employed in constructions in which each course overlaps two or more courses.

As previously mentioned, the invention is applicable to shingles of all suitable materials. It is also applicable to slate shingles having veins 45 or ribbons through which moisture ordinarily rises by capillary attraction or otherwise. This effect of these veins or ribbons may be prevented by coating the backs or lower surfaces of the shingles with a suitable water-proof material, such as a cement or other mixture, or a water-proof cloth or felt or like material. The use of such a water-proof coating is not restricted to slate having veins or ribbons, but is also applicable to shingles of cement or asbestos or any other material where the same conditions apply, that is, the passage of moisture or dampness through the shingles from its lower to its upper side.

The forms of the invention disclosed are preferred forms and changes may be made in the form, location and relative arrangement of the several parts of the constructions disclosed without departing from the principles of the invention. In consequence, the invention is not to be limited excepting by the scope of the appended claims.

What is claimed is:

1. A roof or siding construction comprising a base structure, overlapping courses of shingles on the base structure, felt underlying each course

5 of shingles and overlying the head end portions of each overlapped course, the felt having apertures in the portions thereof between the overlapping portions of the shingles, driven elements for securing the head of the shingles to the base structure, and cementing means in said apertures for securing the felt to the shingles between which it is positioned.

10 2. A roof or siding construction comprising a base structure, overlapping courses of shingles on the base structure, felt underlying each course of shingles and overlying the head end portions of each overlapped course, the felt having apertures in the portions thereof between the overlapping portions of the shingles, driven elements for securing the heads of the shingles to the base structure, and cementing means in said apertures for securing the felt to the head end portions of the shingles in an overlapped course and to the butt ends of the shingles in the overlapping course.

15 3. A roof or siding construction comprising a base structure, overlapping courses of shingles on the base structure, felt underlying each course of shingles and overlying the head end portions of each overlapped course, the felt having apertures in the lower edge portion, driven elements for securing the heads of the shingles to the base structure, and cementing means in said apertures for securing the felt to the head end portions of the shingles in the overlapped course and to the butt ends portions of the shingles in the overlapping course.

20 4. A roof or siding construction comprising a base structure, overlapping courses of shingles on the base structure, felt underlying each course of shingles and overlying the head end portions of each overlapped course, the felt having a plurality of rows of apertures in the lower edge portion, driven elements for securing the heads of the shingles to the base structure, and cementing means in said apertures for securing the felt to the head end portions of the shingles in the overlapped course and to the butt end portions of the shingles in the overlapping course.

25 5. A roof or siding construction comprising a base structure, overlapping courses of shingles on the base structure, felt underlying each course of shingles and overlying the head end portions of each overlapped course, the felt having a single row of apertures in the lower edge portion, driven elements for securing the heads of the shingles to the base structure, and cementing means in said apertures for securing the felt to the head end portions of the shingles in the overlapped course and to the butt end portions of the shingles in the overlapping course.

30 6. A roof or siding construction comprising a base structure, overlapping courses of shingles on the base structure, felt underlying each course of shingles and overlying the head end portions of each overlapped course, the courses being laid in such manner that the head ends only of the shingles in each course are overlapped by but one other course, driven elements for securing the shingles to the base structure, the felt having apertures in the lower edge portion, and cementing means in said apertures for securing the felt to the head end portions of the shingles in the overlapped course and to the butt end portions of the shingles in the overlapping course.
